REMOVABLE RUMBLE SEAT TOP

Earl S. Tupper, Shirley, Mass.

Application August 8, 1932, Serial No. 627,819
Renewed November 10, 1933

23 Claims. (Cl. 296—99)

This invention relates to a removable top to be mounted, as desired, over the rumble seat opening of automobiles of the roadster and similar types. The top, when in position, provides with the back of the seat a complete enclosure for occupants of the rumble seat should such complete enclosure be necessary because of weather conditions but its sides may be dropped when desired. Furthermore the top is built in a collapsible frame that, when folded, may be stored in the rumble and the folding is so accomplished that the stored package will not interfere with the comfort of occupants of the rumble seat who may prefer to ride without the top in place.

The object of the invention is to provide a rumble seat top that may be quickly and readily secured in place; that, while foldable for storage, will be substantially rigid when mounted; and one which may immediately and easily be opened to afford access to the rumble seat and egress therefrom. A further object of the invention is to provide for adjustment to fit rumble seat openings varying in width.

Accordingly one important feature of the invention consists in the provision of a front framework having a foot bar shaped to fit within the front and connecting side gutters of the rumble seat opening and to be clamped therein so that the front frame will stand rigidly across the said opening. The front frame clamps constitute the only fastening devices for the entire top.

A further feature comprises foldable sides, which may be either on a framework or made of material not requiring a stiffening frame, the bottom edges of which are shaped to fit within the side gutters of the rumble seat opening thus to hold them from spreading when the top is in place and eliminate additional fasteners for this purpose. In this connection the back of the seat is preferably utilized to keep the foldable sides from collapsing when the top is in place and to impart rigidity to the structure.

A still further feature resides in mounting the foldable sides on a roof which in turn is pivotally secured to the front framework, thus to permit the sides and roof to be lifted as a unit and to be thrown to a position forward of the front framework to uncover the rumble seat for embarking or debarking of passengers. The uncovering and re-covering after the passengers are seated, is a simple operation because

of the absence of fastening devices upon the side or rear portions of the foldable top.

To the accomplishment of the objects named and such others as may hereinafter appear, as will readily be understood by those skilled in the art, the invention comprises the features and combinations of parts first described in detail hereinafter and then particularly pointed out in its true scope in the appended claims. 5

The nature and scope of the invention will 10 be understood from a description of the preferred embodiment thereof illustrated in the accompanying drawings, in which:

Figure 1 is a view, in perspective, of an automobile fitted with the novel rumble seat top of 15 this invention;

Fig. 2 is a view similar to Fig. 1 looking at the rear of the automobile;

Fig. 3 is a view, in perspective, of the framework employed in the manufacture of the preferred form of the invention, dot and dash lines 20 being applied to the framework to indicate how it is covered; and

Fig. 4 is a view, in longitudinal section through the rumble seat top as secured to the automobile 25 in position enclosing the rumble seat opening, a part of the automobile body being broken away to show the opened seat, and a part of the side gutter being broken away to show how the overlapping front and side frames are seated 30 therein. The dotted lines indicate how the rumble seat top is opened for entrance and egress of passengers to and from the rumble.

In the embodiment of the invention illustrated in the drawings a skeleton framework, comprising a front frame, roof frame and two side frames, is employed to support the covering material, these frames being so hinged together as to be foldable into a more or less flat package 35 capable of being stored in the rumble compartment when not erected over the rumble seat, but it is within the scope of the invention to provide a roof and sides of any suitable material for the purpose intended and to hinge these members together in the manner illustrated. 40

The preferred construction (see Fig. 3) includes a front frame comprising a single length of wire bent to inverted U-shape to form a top rail 10 and side rails 11. Each side rail turns rearward and then doubles back upon itself 50 forming two relatively short side bottom rails 12. The free ends 13 of the frame wire turn inward beneath and parallel to the top rail and are received in the ends of a tube 14 that is shorter than the top rail. This structure forms a width- 55

wise adjustable bottom rail adapting the front frame, by springing the side rails out or in, to the differing widths of rumble seat openings which vary a few inches on different makes of 5 automobiles. It will be understood that the covering material will be fitted on the front frame when extended to its greatest required width and will be caused to wrinkle slightly at each side of the window therein when the bottom 10 rail is adjusted for a narrower rumble seat opening or for reducing the folded top to a convenient width for storage. Obviously the front frame may be specially made to fit a particular rumble seat opening. In such case the free ends 13 may 15 be welded or otherwise connected and the tube 14 omitted. Preferably, but not necessarily, the front frame is braced by rods 15 connecting the rear end of each bottom side rail 12 with the adjacent end of the top rail 10.

20 The roof frame comprises a wire bent to U-shape to form a rear rail 16 and side rails 17. The forward ends of the side rails 17 are hinged on the top rail 10 of the front frame. An upwardly curved cross brace 18 toward the rear 25 of the roof affords additional head room above the rumble seat.

Each side frame comprises a wire bent to general U-shape having a bottom rail 19 shaped to fit the curve of the rear body of the automobile 30 at each side of the rumble seat opening, a front rail 20 and a rear rail 21 which may be bowed rearwardly to the general curvature of the raised back 22 of the rumble seat. The rails 20 and 21 of each side frame are pivotally connected to a 35 roof side rail as shown. Preferably a cross brace 23 connects the front and rear rails of each side frame for stiffening and to use as handles for opening and closing the top from inside as presently to be described.

40 The shape of the rumble seat top and the relation of the front, roof and sides to each other is illustrated by Figs. 1 and 2, and the manner of securing the top to the automobile is disclosed by Fig. 4. The rumble seat opening is provided 45 with a gutter at both front and sides. When in position for enclosing the rumble seat the bottom rail of the front frame seats in the front gutter 24 and the two short bottom side rails, completing the foot bar, seat in their respective side 50 gutter 25. Clamps 26 are provided for holding the front frame in the gutter and this is the sole fastening required. Conveniently, but not necessarily, each clamp 26 is permanently secured to a bottom side rail 12. In the form of clamp illustrated the upper end 27 of the metal plate from which the clamp is formed is rolled about one of the doublings of the rail 12 so that the clamp is pivotally connected to and depends from this rail. The lower end 28 is turned outward and carries a clamping screw 29. In fitting the front frame to the automobile the two clamps are swung upward and after the frame is seated in the gutter the clamps are turned downward to place their screws inside the rumble and beneath 55 the body of the automobile. On tightening the clamps the front frame is held rigidly in place by the gutter and the clamps bearing upon the bottom side rails 12 and the underlying automobile body.

60 It will be observed that the side frames overlap the front frame when the entire framework is in place with the curved bottom rail 19 of each side frame seated in its respective side gutter 25. The length of the side frames is such 65 that each curved rear rail 21 may abut an end

of the opened rumble seat back 22, thus bracing the sides against collapsing inward and adding to the fore and aft rigidity of the entire top. The bracing by the seat back ordinarily is sufficient, but to insure rigidity of the framework just at the rear of the front frame each clamp 5 may be provided with a rearwardly extending retaining bar 30 which bears against the inner side of a front rail 20 to prevent an inward movement of the forward portion of a side-member 10 should it be released from the retaining side walls of the gutter.

Any suitable covering material may be applied in any ordinary or convenient manner to the various frames herein described, or the sides and 15 roof may be formed of a material inherently stiff enough not to require bracing by framework. The covering of the front and side frames will, conveniently, be provided with windows forming a part of the covering. In fair weather, 20 when the top may be used merely as a sun shield the side coverings may be detached. To this end each side covering has two parallel, vertical slits 31 extending from about the cross brace 23 upward to the top edge and the portion between 25 the slits is unsecured or detachably secured to the roof member. Multiple hookless fastenings, accessible from inside, may be used to close the slits. Thus substantially an entire side may be dropped inward over a cross brace 23 at the 30 will of the passenger. The covering of the front frame may be fitted with multiple hookless fastenings in the same manner providing for an open or closed windshield as may be desired.

It is preferred to employ a skeleton framework 35 as shown in Fig. 3 and to cover the several members with the same material as is used by automobile manufacturers for the tops over the driver's seat. Such coverings are best illustrated in Figs. 1 and 2. The back of the 40 opened rumble seat provides the greater part of the back of the rumble seat top and conveniently the remaining portion of the back may be formed by a back flap or curtain 32 (Fig. 4) in continuation of the roof covering. This curtain may 45 have windows if desired. In order to protect the interior from rain driving in, especially along the tops of the sides, the back curtain has side wings 33 (Fig. 2) of generally triangular shape lying outside of the covering on each side member. 50

In some makes of automobiles there may not be room to fit the rear rails 21 or rear edges of the side members of the rumble seat top, outside of the ends of the opened rumble seat back 55 as is preferred for the most efficient bracing of the side members. In such cases the side members must be sprung forward slightly and their rear edges fitted against the opened seat back, between its outer edges and the ends of the upholstered 60 at its forward face as indicated in Fig. 2.

After the top is in position enclosing the rumble seat opening, access or egress may be had by manipulating the top in the following manner. The roof and sides, being unsecured to the automobile body, may be lifted as a unit from the side gutters, first springing the top slightly ahead for clearance if necessary. After clearing the 70 back of the rumble seat the sides may be folded inward (they naturally will fall inward due to the character of the coverings) and these three-folded members are then thrown over forward of the front frame as shown by dotted lines in 75

Fig. 4. Thus the rumble is as free for entrance as though no top had been applied. After entering the rumble the passenger swings the roof back into position permitting the sides to drop down and, from inside the rumble, fits the bottom rails 19 into the gutters 25 bracing them by the seat back 22, and rods 30 if present, as heretofore described. The back curtain 32 naturally falls outside the seat back 22.

10 For storage purposes, after unclamping the rumble seat top, the two sides, the back flap collapsing inward between them, are folded in at the under side of the roof and these three members are folded down as a unit at the inner face 15 of the front frame. The package thus formed is substantially flat and, in certain makes of automobiles, can be retained in vertical position at the front end of the rumble where it does not interfere with foot room, or in other makes of 20 automobiles can be laid flat beneath the driver's seat. The package is relatively small and light and can readily be handled by one person either from within or without the compartment in detaching and folding or in unfolding and attaching. 25

It will be clear to those skilled in this art, and with the general objects of the present invention in view, that changes may be made in the details of structure the described and illustrated embodiment of the invention being intended as an exploitation of its underlying essentials, the features whereof are stated in their true scope in the claims herewith.

That which is claimed as new, is:—

35 1. A removable top for the rumble seat of an automobile in which the rumble seat opening presents a gutter at its front and sides, comprising a front frame having a front bottom rail to seat in said front gutter and two relatively 40 short side bottom rails to seat in said side gutters, means for detachably securing said frame in place, a roof member connected to said front frame and side members connected to said roof member.

45 2. The invention of claim 1 in which the said bottom rail of the front frame is adjustable to fit within front gutters of rumble seat openings varying in width.

3. The invention of claim 1 in which said 50 means for securing the front frame in place comprises manually releasable clamping members secured to and forming a permanent part of said front frame.

4. A collapsible top for rumble seats of 55 automobiles including a front frame comprising a top rail and side rails formed by an inverted U-shaped member having a portion reversely bent upon itself at each side and directed rearwardly to form doubled side bottom rails and 60 the free ends directed inwardly beneath the top rail to form a front bottom rail, a roof frame comprising a U-shaped member forming rear and side rails, said side rails being pivotally connected to said top rail of the front frame, and 65 two side frames each comprising a generally U-shaped member forming a bottom rail and front and rear rails each pair of the latter being pivotally connected to a side rail of the roof frame.

70 5. The invention of claim 4 in which the front is stiffened at each end by a tie rod, each of said rods extending from an end of the top rail to the rear end of the underlying side bottom rail.

6. The invention of claim 4 in which a clamping member is secured at each side of the front

frame to one of the doublings of the doubled side bottom rails thereof.

7. The invention of claim 4 in which the roof frame is stiffened by a bowed cross rod between the two side rails thereof, and each side frame is stiffened by a cross rod between the front and rear rails thereof. 5

8. For use with an automobile having a rumble seat opening presenting a gutter at its front and sides, a rumble seat top comprising a front frame having a bottom rail shaped to seat in said front and side gutters, two side frames having bottom rails shaped to seat in said side gutters and a roof frame all suitably covered, and means for detachably securing said top to 10 the automobile in position above said rumble seat opening. 15

9. The invention according to claim 8 in which said means for securing the top consists of manually operated clamps for bearing upon a 20 bottom frame rail and the automobile body to hold said rail in the gutter.

10. A top for rumble seats of automobiles comprising a covered framework shaped at its bottom edge to fit within the gutter about the 25 rumble seat opening, and means for detachably retaining the top in position by holding said bottom edge in said gutter.

11. The invention of claim 10 in which the framework comprises connected front, side and 30 roof members and the means for detachably retaining the top in position acts solely upon the front member.

12. An automobile rumble seat top comprising a framework including skeleton side frames 35 shaped to enclose the rumble seat opening from the raised back of the seat forward, each side frame having a substantially horizontal cross brace, covering on said side frames, and parallel vertical slits in the covering extending from the 40 upper edge thereof down to said cross brace, said upper edge between the slits being unsecured forming a curtain flap, and multiple hookless fastenings at said slits for attaching and detaching said flap. 45

13. A removable rumble seat top for automobiles comprising a front frame having a bottom rail fitting in the front gutter of the rumble seat opening, a roof and two sides, each side having a bottom edge fitting into a side gutter 50 of the rumble seat opening and having its top edge pivotally connected to the roof for folding thereupon when the top is removed from the automobile, said sides being braced from collapsing inward by extending their rear edges 55 to lie one at each end of the open back of the rumble seat.

14. The invention according to claim 13 in which additional provision against inward collapse of the sides comprises rigid means carried 60 at each side of said front frame for bearing against the inner faces of the forward edges of said sides.

15. An automobile rumble seat top for enclosing the rumble seat opening comprising a roof, 65 a front and sides secured in the gutter of the rumble seat opening, all suitably covered, and a back formed partially by the back of the open rumble seat and partially by covering on the rumble seat top. 70

16. An automobile rumble seat top comprising a covered front frame, a roof hinged at its forward edge to said front frame, side frames each hinged at its upper edge to a side of the roof and unconnected to the front frame, and means 75

for clamping said top to the automobile by its front frame only, whereby the roof may be lifted on its hinge to the front frame and the sides folded inward thereupon to uncover the rumble seat.

17. A collapsible top dimensioned to enclose the rumble seat opening of an automobile comprising a roof, a front and two sides each independent of the other, said front being hingedly hung from the forward edge of the roof and said sides being hingedly hung from the side edges of the roof whereby the sides may be separately folded inward under the roof and said three collapsed members may be folded downward as a unit at the back of said front producing a flattened package for storage purposes with the sides lying between the front and the roof.

18. The invention of claim 17 in which said roof is provided with a curtain depending from its rear edge forming a back and consisting of flexible material to fold inward and lie between the sides and the roof when the top is collapsed.

19. A removable and collapsible top for the rumble seat opening of an automobile consisting of a front having sufficient rigidity to stand in the front gutter of said opening, sides having sufficient rigidity to stand in the side gutters of said opening, a roof to which the top edges of said front and sides are hingedly connected, the bottom edge of each rigid side extending in the gutter from said front to the opened rumble seat back, and means for detachably securing said top in said gutter independently of the opened seat back.

20. The invention of claim 19 in which said securing means consist of removable clamps

holding said front rigidly erect in the front gutter leaving the sides unsecured but held in the side gutters by being braced between said front and said opened rumble seat back.

21. A foldable top for the rumble seat of an automobile comprising a covered front frame having angular side wings to stand in the front corners formed by the front and side gutters of the rumble seat opening, means for clamping said front frame in place, a covered roof frame and sides depending from the side edges of said roof frame each shaped at its bottom edge to seat in a side gutter of the rumble seat opening and to extend from said covered front to the raised back of the rumble seat, said sides each being hinged to the roof frame and said roof being hinged to the front frame whereby the roof and sides may freely be lifted as a unit relatively to the front and folded together to uncover the rumble seat opening.

22. A foldable frame for a covered top for the rumble seat of an automobile comprising a rectangular wire front comprising top, bottom and side rails, a U-shaped wire top comprising rear and side rails said side rails and the top rail of said front frame being hingedly connected, and generally U-shaped wire sides comprising bottom, forward and rear rails, the forward and rear rails of each side and a side rail of the top being hingedly connected.

23. The foldable frame defined by claim 22 in which said wire front includes side wings each formed by a wire extending rearwardly from an end of the bottom rail and then upwardly to the end of the top rail at that side of the front.

EARL S. TUPPER.
